UNITED STATES PATENT OFFICE.

LOUIS F. KINDELMANN, OF PITTSBURGH, PENNSYLVANIA, ASSIGNOR TO WESTINGHOUSE ELECTRIC & MANUFACTURING COMPANY, A CORPORATION OF PENNSYLVANIA.

GLOW-DISCHARGE TRANSMITTER CASING.

Application filed May 7, 1923. Serial No. 637,052.

To all whom it may concern:

Be it known that I, LOUIS F. KINDELMANN, a citizen of the United States, and a resident of Pittsburgh, in the county of Allegheny and State of Pennsylvania, have invented a new and useful Improvement in Glow-Discharge Transmitter Casings, of which the following is a specification.

My invention relates to telephone systems and apparatus, having particular reference to the mechanism required for sound wave translating devices.

Broadly speaking an object of my invention is to provide a protecting and supporting casing for a telephone transmitter of the glow discharge type.

An object of my invention is to provide a casing for the support and protection of glow discharge telephonic transmitter which will give adequate reception of sound waves and which will also provide for the support and protection of necessary resistance and control units required for the glow discharge.

A further object of my invention is to provide for the attachment of leads and terminals and to furnish protection against the influence of nearby high power radio frequency electrostatic and magnetic fields.

In the co-pending application of P. Thomas, Serial No. 600,822, filed November 14, 1922, for improvement in glow discharge transmitters, there is described the principle of operation and the essential structures for applying that principle whereby a glow discharge is made to serve as a telephonic transmitter. It is desirable for the best operation of this device that the electrodes between which the glow discharge is maintained be supported in a detachable structure, which in turn is desirably supported in a casing which will also support the resistance and control elements and the terminal and connector structures. It is also desirable that the casing have a metallic shield to protect the various elements of the glow discharge transmitter from the influence of nearby electrostatic or electromagnetic fields which may sometimes be encountered when the transmitter is used in the neighborhood of a high power radio transmitting station.

In the practice of my invention, I provide a block of maple wood or other suitable insulating material in which suitable recesses

are cut for the various elements required to make up the transmitter assembly. This maple block serves for both insulation and support. It is surrounded by a metal case and cover which are grounded. The metal case and cover form the necessary shield for protection against the previously mentioned electrostatic and electromagnetic field.

Other objects and applications of my invention, as well as details of construction will be apparent from the following description when taken in connection with the accompanying drawings, wherein—

Figure 1 is a front view of my apparatus, and

Fig. 2 is a central vertical section thereof.

In Fig. 1, 1 is a maple block in which there is a recess for holding the glow discharge capsule 2 and also recesses for its supporting and connecting clips 3, 4 and 5. Other recesses are provided as shown for resistance rods 6 and 7. Channels are provided for connecting wires 8, 9 and 10. All these openings are made by drilling through the body of the block and plugging the unnecessary parts of the drilled holes with maple or other suitable material. Additional openings are provided for clips 12 and 13 and for the shielded cables 14 and 15 and also for anchoring clips 16 and 17. The clip 17 is connected as shown at 26 in Fig. 2 to the case 18. If desired, the clip 16 may also be thus connected but it is unnecessary to connect both clips because the metallic outer covers of the wires 14 and 15 are connected at a point outside the figure.

A metal shielding case 18 is provided surrounding the rim and back of the block 1. A wooden cover 19 shown in Fig. 2, is also provided which extends slightly beyond the block 1 so as to bring its circumferential surface flush with the outside of the case 18. It is covered with a metal shield 21. A group of holes 22 are provided passing through the maple block from the opening in which the glow discharge capsule is supported. These holes are protected at their front ends by a felt pad 23. An inlet opening in the cover is shielded with a light fabric covering 24, this shielded opening allowing sound waves to enter the transmitter and affect the glow discharge. The various parts are held in place by sundry suitable screws and fastenings as shown.

In assembling the device, the wires 8, 9 and 10 are inserted in their respective ducts and connected to the several clips at the same time that the latter are fastened to the block by screws. The cell 2 is put into its recess and the projecting ends of its electrodes co-operate with the clips 3, 4 and 5 to hold the cell in place and also establish the connections. The wires 14 and 15 are then inserted in the clips 12, 13, 16 and 17, the clips 12 and 13 providing the connections to the wires and the clips 16 and 17 providing connections to the metallic covering on the outside of said wires. The insertion of resistances 7 and 8 completes the set and the cover 19 is then put in place. The shield 21 is secured to the cover by the screws fastening the fabric 24 in place and is put on to the device at the same time as the cover and by frictional contact with the case 18 holds the cover on.

In operation, this device makes it convenient to prepare the transmitter for the reception of sound, and give it the necessary support and protection. The clip also permits ready removal or insertion of lead wires 14 and 15 and of resistances 7 and 8. The glow discharge capsule is likewise held in spring clips which provide convenient means for its removal and replacement by other glow discharge capsules.

The rear end of the glow discharge capsule is protected by a padding of felt 23 which is likewise held in proper operative relation by the construction of the device. The group of holes 22 serves to provide protection against sounds which might enter the rear end of the glow discharge capsule. The front of the glow discharge capsule 2 is protected against dust and other objectionable influences such as drafts by the light fabric 24 which is also held in position by the device. The casing shield 18 and cover shield 21, which are integral parts of the device, are of metal and are connected to the grounded conductor covers 14 and 15, thus forming a shield which is essential for protection of the glow discharge from electrostatic and electromagnetic influences which may be produced by outside sources.

By the construction as above described and by modifications thereof which will readily be apparent to those skilled in the art, it is possible to provide a supporting and insulating structure for the glow discharge capsule which will maintain it in operative relation with the necessary circuit parts and also protect it against undesired influences such as dust, extraneous sounds and electrostatic and magnetic fields.

While I have shown only one embodiment of my invention in the accompanying drawings, it is obvious that many changes and modifications may be adopted without de-

parting from the spirit thereof: It is desired, therefore, that only such limitations shall be imposed upon my invention as are indicated in the prior art or set forth in the appended claims.

I claim as my invention:

1. A glow discharge transmitter case comprising a body of insulating material recessed to provide chambers for the various elements of a glow discharge transmitter, and a metallic shield, and said body and shield being perforated for the entrance of sound wave disturbances.

2. A glow discharge transmitter case comprising a body portion of insulating material, having recesses for the various elements of a glow discharge transmitter, suitable clips for supporting said elements and having operative connection thereto, a metallic covering shield and sound-conveying and damping means cooperating therewith.

3. A glow discharge transmitter case for holding the parts of a glow discharge transmitter comprising a body of insulating material, sound conveying and damping means, and a covering shield of metallic material, said body holding the transmitter parts in proper position for operative relation.

4. A housing for a telephone transmitter of the glow discharge type comprising a block of insulating material having recesses therein and a metallic shield therearound clips secured to said body adjacent to each of said recesses, said body also having canals connecting said recesses and wires in said canals for connecting said clips.

5. In a telephone transmitter of the glow discharge type, a sound responsive device, a housing enclosing electrical apparatus and said means, wires leading into said housing and connected to said apparatus, metallic sleeves covering each of said wires, a metallic casing enclosing said housing and insulated from the electrical apparatus therein, means connecting said casing to said sleeves and means for the ingress, control and damping of sound.

6. In a telephone transmitter of the glow discharge type, a sound responsive device, a housing enclosing electrical apparatus, and said means, wires leading into said housing and connected to said apparatus, metallic sleeves covering each of said wires, a metallic casing enclosing said housing and insulated from the electrical apparatus therein, clips connecting said sleeves and holding said wires in place, said clips being electrically connected to said casing and means for the ingress, control and damping of sound.

In testimony whereof, I have hereunto subscribed my name this 27th day of April 1923.

LOUIS F. KINDERMANN.
